UNITED STATES PATENT OFFICE.

JOHN R. DEAN, OF NORTH GIRARD, PENNSYLVANIA, AND AUGUST W. HOLMBERG, OF NEW YORK, N. Y., ASSIGNEES, BY DIRECT AND MESNE ASSIGNMENTS, OF ONE-THIRD TO WALTER K. DEAN, OF NORTH GIRARD, PENNSYLVANIA, AND TWO-THIRDS TO SAID JOHN R. DEAN.

PUNCHING-MACHINE.

1,112,601.

Specification of Letters Patent.

Patented Oct. 6, 1914.

Application filed November 22, 1913. Serial No. 802,408.

To all whom it may concern:

Be it known that we, JOHN R. DEAN, a citizen of the United States, residing at North Girard, in the county of Erie and 5 State of Pennsylvania, and AUGUST W. HOLMBERG, a citizen of the United States, residing at New York, in the county of New York and State of New York, have invented new and useful Improvements in Punching- 10 Machines, of which the following is a specification.

This invention relates to punching machines and consists in certain improvements in the construction thereof as will be hereinafter fully described and pointed out in 15 the claims.

More particularly the invention relates to punching machines especially adapted for punching garment stays as A formed with 20 alternate slots as A' extending inwardly from opposite sides of the stay.

The object of the invention is to provide a machine which will simplify the punching of such stays and improve the product.

25 The details of the invention will appear from the specification and claims.

The invention is illustrated in the accompanying drawings as follows:

Figure 1 shows a side elevation, partly in 30 section of the punching machine. Fig. 2 is a section on the line 2—2 in Fig. 1. Fig. 3 is a plan view of the machine, the driving mechanism being removed. Fig. 4 is a side elevation partly in section on the line 4—4.

Fig. 5 is a section of the clutch mechanism, 35 forming part of the feeding apparatus on the line 5—5 in Fig. 6. Fig. 6 is a section of the same parts on the line 6—6 in Fig. 5.

Fig. 7 is a section on the line 7—7 of the die 40 clamps on the punching head. Fig. 8 is a section on the line 8—8 in Fig. 7. Fig. 9 is a section on the line 9—9 in Fig. 7.

1 marks the base of the machine, 2 the die block and 3 the female die. This has 45 the openings 4 these being slightly off-set as shown in Fig. 1. A guide plate 5 is arranged over the die 3 and has guide openings 6 corresponding to the openings 4. The punching head 7 has the yoke 8 from which 50 extends the guide pins 9. These enter the openings 10 in the block 2 and guide the punching head. The male dies 11 and 12 are formed of thin strips of steel and these

are held in an especially designed clamp. The dies are off-set so as to conform to the 55 openings 4. The inner sides of the die that is to say that side of the die which is next to the inner end of the slot formed in the stay is slightly longer than the remainder of the cutting surface of the die forming a 60 point 13 and the cutting edge 14 as clearly shown in Fig. 9. This is necessary in that by beginning at the inner end of the slot in this manner and then following out the cutting with a shearing action the material 65 of the stay is not distorted so as to interfere with the regularity of the slots. We form a guide extension 15 at the outer side of the die and this moves into the slot 4 at the same time that the point 13 enters the part 4. It 70 will be understood, however, that this is outside of the stay and simply forms a guide. This arrangement of the dies, that is, having a plurality of dies off-set so as to make the alternate slots extending inwardly from 75 opposite sides of the stay and arranging these dies in series so that the front die is at one edge of the stay and the rear die is at the opposite edge of the stay makes it possible to punch sections of the stay and then 80 simply move the stay forward and obtain a continuity in the arrangement of the slots. It is desirable to have the stay punched entirely from one side in that the condensing of the metal due to the punching action 85 stiffens the stay in one direction and adds to its resiliency. It is also necessary that the crossings formed between the slots should be of equal cross section as otherwise the smaller cross section would be subjected 90 to undue strain and the stay would soon break at the point of this weakness. By punching the stay in sections this regularity may be more nearly attained and the punching may be done from one side of the stay 95 and by punching from the center outwardly the separating of the stay so as to interfere with the proper spacing is largely obviated.

The clamp for holding the punching dies 100 11 and 12 comprises the head 16 on which are arranged the jaws 17. The dies are placed in the slots 18 and the jaws force the dies against the inner surface of these slots. The jaws 17 are pivoted on pins 19 and have 105 cam surfaces on their lower faces which en-

gage the tapered or inner cam surface of the sleeve 20. The sleeve 20 is screwed on to the head and as it is screwed up the cam surfaces operating one on the other force the jaws inwardly thus clamping the dies in place. In order to give a secure base for the dies we prefer to place the keys 21 in transverse slots 21^a at the upper end of the dies.

10 The driving and feeding mechanism of the machine may be varied but we prefer that shown. The driving shaft 22 is mounted in bearings 23—23 in the uprights 24, the uprights carrying the guides 25 for the 15 punching head. The punching head is driven by the eccentric 26 through the eccentric strap 27. The usual fly-wheel 28 is provided.

10 A crank disk 29 is arranged at the end of 20 the shaft opposite the fly-wheel 28. It has an undercut slot 30 arranged in its face in which is arranged a sliding block 31. The block can be adjusted by means of a screw 32 and the screw locked in adjustment by 25 means of a jam nut 33. A crank pin 34 extends from the block 31. It will be readily seen that by shifting the block 31 the throw of the crank may be varied as desired. A link 35 connects the crank with a pin 36 30 on a crank disk 37. The crank disk 37 is fixed on the shaft 38 and the shaft 38 is journaled in bearings 39 arranged on a post 39^a extending from the base 1. A clutch member 40 is fixed on the shaft 38. This 35 clutch member has a sleeve formed within it and a second clutch member 41 is arranged within the sleeve. The clutch member 41 has a series of cam surfaces 42 on which rollers 43 are arranged, the rollers 40 being yieldingly forced against the inner surface of the sleeve by the springs 44, the springs extending into the sockets 45 in the member 41. In this way a very sensitive clutch is provided which readily releases 45 when pressure is exerted in one direction but immediately engages when moved in the opposite direction. As the crank 34 is rotated it oscillates the crank 37 and these oscillations working in one direction 50 through the clutch member 40 move the clutch member 41 while on the return movements the clutch member 41 remains stationary. These movements of the clutch are timed with relation to the punch so that the 55 forward movement of the member 41 takes place when the punch is in its upper position and the return movement takes place when the punch is in its operative or lower position.

60 The member 41 is fixed on a shaft 46 and this is mounted in the bearings 47 carried by the base. A beveled gear 48 is fixed on the shaft 46 and meshes a beveled gear 49. The beveled gear 49 is fixed on a cross shaft 50 65 which extends across the machine in posts

51—51. A gear 53 is arranged at the opposite end from the gear 49 and meshes a gear 54 arranged directly above it. The gear 54 is fixed on a shaft 55 extending across the machine and directly above the shaft 50, the shaft 55 being carried in bearings in the post 51. Rolls 56 are arranged on the shafts 50 and 55 and engage the stay between them. A series of gears 57, 58, 59 and 60 are arranged along the base of the machine and 70 drive the shaft 61. The shaft 61 extends across the machine and is arranged in bearings in the posts 60^a—60^a. The gear 60 meshes a gear 62 immediately above it, the gear 62 being fixed on the shaft 63 extending across the machine and mounted in bearings arranged in the posts 60^a—60^a. Rolls 64 and 65 are arranged on the shafts 63 and 61 respectively and engage the opposite sides of the stay A. The throw of the 85 crank 37 may be varied by means of the adjustable block 31 and is so varied that a feeding movement is given to the rolls to carry a section of the stay just equal to the amount punched forward with each cycle 90 of the machine. In this way the punching action is continuous and automatic extending through the entire stay or it may be continued through an indefinite length of the material. 95

What we claim as new is:—

1. In a punching machine for forming garment stays having slots formed therein extending alternately inwardly from opposite sides of the stay, the combination of 100 a die actuating head; and a plurality of punching dies off-set to form slots extending from opposite sides of the stay, the dies overlapping and operating from opposite sides of the stay. 105

2. In a punching machine for forming garment stays having slots formed therein extending alternately inwardly from opposite sides of the stay, the combination of 110 a die actuating head; and a plurality of punching dies off-set to form slots extending from opposite sides of the stay, the forward die being at one side of the stay to be punched and the rear die at the opposite side of the stay to be punched whereby 115 the stay may be punched in sections forming a continuity in the arrangement of the slots, said dies being longer at their inner sides and severing the metal of the stay from the inner ends of the slots outwardly. 120

3. In a punching machine for forming garment stays having slots formed therein extending alternately inwardly from opposite sides of the stay, the combination of a die actuating head; and a plurality of 125 punching dies off-set to form slots extending from opposite sides of the stay, the forward die being at one side of the stay to be punched and the rear die at the opposite side of the stay to be punched whereby the 130

stay may be punched in sections forming a continuity in the arrangement of the slots, said dies being longer at their inner sides and severing the metal of the stay from the 5 inner ends of the slots outwardly, said dies being also provided with guide extensions at their outer sides.

4. In a punching machine for forming garment stays having slots formed therein 10 extending alternately inwardly from opposite sides of the stay, the combination of a die actuating head; a plurality of punching dies off-set to form slots extending from opposite sides of the stay, the forward die 15 being at one side of the stay to be punched and the rear die at the opposite side of the stay to be punched whereby the stay may be punched in sections forming a continuity in the arrangement of the slots; and 20 means for feeding the stay to correspond to the section punched.

5. In a punching machine for forming garment stays having slots formed therein 25 extending alternately inwardly from opposite sides of the stay, the combination of a die actuating head; a plurality of punching dies off-set to form slots extending from opposite sides of the stay, the forward die being at one side of the stay to be punched 30 and the rear die at the opposite side of the stay to be punched whereby the stay may be punched in sections forming a continuity in the arrangement of the slots; and feeding means operating rotatively on the stay.

35 6. In a punching machine for forming garment stays having slots formed therein extending alternately inwardly from opposite sides of the stay, the combination of a die actuating head; a plurality of punching dies off-set to form slots extending from 40 opposite sides of the stay, the forward die being at one side of the stay to be punched

and the rear die at the opposite side of the stay to be punched whereby the stay may be punched in sections forming a continuity 45 in the arrangement of the slots; means for feeding the stay forward intermittently as punched; and means for adjusting the distance which the stay is fed at each cycle of the machine.

50 7. In a punching machine for forming garment stays having slots formed therein extending alternately inwardly from opposite sides of the stay, the combination of a die actuating head; a punching die carried 55 by the head and having the side toward the inner end of the slot forming the stay longer than the opposite side whereby the metal is severed at the inner end of the slot and the cutting action continued from 60 the inner end of the slot toward the outer end of the slot.

8. In a punching machine for forming garment stays having slots formed therein 65 extending alternately inwardly from opposite sides of the stay, the combination of a die actuating head; a punching die carried by the head and having the side toward the inner end of the slot forming the stay longer than the opposite side whereby the 70 metal is severed at the inner end of the slot and the cutting action continued from the inner end of the slot toward the outer end of the slot, said punching die having a guiding extension on its outer side.

75 In testimony whereof we have hereunto set our hands in the presence of two subscribing witnesses.
